UNITED STATES PATENT OFFICE.

MATHEW WILSON, OF GARRISON, IOWA.

DESIGN FOR A BRIDLE-FASTENER BLANK.

SPECIFICATION forming part of Design No. 30,097, dated January 31, 1899.

Application filed January 6, 1899. Serial No. 701,403. Term of patent 7 years.

To all whom it may concern:

Be it known that I, MATHEW WILSON, a citizen of the United States, residing at Garrison, in the county of Benton and State of

5 Iowa, have invented and produced a new and original Design for a Bridle-Fastener Blank, of which the following is a specification.

This invention relates to a new and original design for a bridle-fastener blank; and it has 10 for its object to provide a design of this character that shall be both useful and ornamental.

The leading feature of the design resides in an approximately rectangular flat plate 15 provided at its corners with laterally-projecting V-shaped ears and having at one end, within the plane thereof, a rectangular extension-wing provided at one side edge with a plurality of angular prongs.

20 While the essential feature of the design resides in the plate provided with the lateral V-shaped ears and the extension-wing having angular prongs at one edge, the invention embodies certain minor features, which

25 are the main rectangular plate having a convexed edge at the end opposite the extension-wing thereof, circular perforations in the laterally-projecting V-shaped ears, and oppositely-located V-shaped notches in the side

30 edges of the blank at the juncture of the main plate with the extension-wing.

In the drawings, Figure 1 is a perspective view of a bridle-fastener blank embodying the herein-described design. Fig. 2 is a plan view thereof.

35 Referring to the accompanying drawings, the numeral 1 designates an approximately rectangular flat body-plate provided at the side edges and corners thereof with laterally-projecting V-shaped ears 2, having circular 40 perforations 3 therein. At one end the said rectangular body-plate 1 is provided with a convexed edge 4, and at the end opposite said convexed edge 4 is formed within the plane thereof with a rectangular extension-wing 5, 45 which extension-wing is provided at one side edge with a plurality of angular or V-shaped prongs 6. At the juncture between the main body-plate 1 and the extension-wing 5 thereof there are formed in opposite side edges of 50 the blank the oppositely-located reentrant V-shaped notches 7.

What is claimed is—

The design for a bridle-fastener blank, herein shown and described.

55 In testimony that I claim the foregoing as my own I have hereto affixed my signature in the presence of two witnesses.

MATHEW WILSON.
